UNITED STATES PATENT OFFICE

ROBERT FOSTER, OF CHICAGO, ILLINOIS, ASSIGNOR TO METAL TRAFFIC MARKER CORPORATION, OF NEW YORK, N. Y., A CORPORATION OF NEW YORK

SURFACE MARKER

Application filed May 18, 1927. Serial No. 192,178.

The object of the invention is to provide improvements in surface markers broadly, and more specifically in markers employed upon highways, passageways, streets and in factories and industrial plants, and safety zones along car lines, to guide motorists and pedestrians at crossings, curves, etc., or to define limits of areas for parking and the like, as well as to be arranged in the form of figures, symbols and other possible indicia intended to convey definite information.

Another object is to provide a marker, comprising a disc-like head, having means adapted to enter and secure the same to any desired surface, which will be referred to hereinafter as a road surface, the under side of said head resting directly upon and therefore being directly supported by said road surface, while the uppermost or exposed surface of said head is characterized by a relatively high coefficient of light reflection and refraction due to said head being formed of or covered by a film or coating of a substantially non-corrosive material, such for instance as nickel, stainless steel, ascoloy, or Monel metal.

A further object is to provide a structure comprising a disc-like head and means for securing the same to a road surface in combination with a sheet, plate or other type of sheathing, said sheathing comprising suitable light-refracting non-corrosive material, and being secured to said head in any suitable manner, such for instance as by inwardly turning or crimping the peripheral edge portion of the sheathing about the corresponding periphery of said head.

Still another object is to provide a marker, comprising a disc-like head, having a preferably integral attaching means comprising a body portion, the lower end of which is recessed and the walls of said recess being notched at intervals to provide intervening downwardly tapering prongs or spikes, adapted to be driven into a road surface and in which surface the tapered free end portions of said spikes tend to flare outwardly and thereby cooperate in preventing the ready removal of the marker from the road surface.

Still furthermore, while the present invention is described as comprising a light-reflecting metallic sheathing, originally separate and then secured to the head of the marker, the scope of the invention is to be understood as comprising the covering of the marker head with any suitable metal or alloy by electroplating, by chemical deposit, or amalgamation, by dipping in suitable material, by coating with enamel, or the like, or in fact by marking the head alone, or the entire structure, of suitable metal or other material by which the marker is sufficiently discernible under ordinary conditions in contrast to the surrounding surface of the highway, or other surface.

With these and other objects in mind, the present invention comprises further details of construction and operation which are fully brought out in the following description when read in conjunction with the accompanying drawings in which Fig. 1 is a side elevation of one embodiment of the invention; Fig. 2 is a vertical diametrical section of the same in operative position in a road or other surface, and Fig. 3 is a bottom plane view of the device as shown in Fig. 1.

Referring to the drawings, the present invention comprises a disc-like head 5, having a convexly curved upper surface 6 and a lower substantially plane surface 7, while from the central portion of said head there extends normally downwardly the shank 8 of an attaching means, the lower end portion of which is provided with an axially inwardly tapering recess or cavity 9, providing a surrounding wall, which in turn is provided with cut-out regions 10 between which are positioned downwardly tapering spike-like projections or prongs 11.

The outer surfaces of these spike projections lie in the plane of and comprise extensions of the outer surface of the shank 8, while the inner surfaces of these prongs slant in such manner as to insure their free ends being decidedly pointed.

With this construction, it will be readily seen that the marker can be stood upon a road surface and driven by means of a sledge hammer or the like until the under surface of

the head 5 rests firmly and uniformly upon the road surface and in which position the attaching member 8 is completely imbedded in the material of the road and the free end portions of the prongs have spread radially outwardly as shown in Fig. 2, thereby serving to resist the accidental shifting or removal of said marker from the road surface.

As illustrated, in the drawings, in order to insure a permanent light-reflecting characteristic of the upper surface of the head 5, a plate 12 of suitable material, such as one of those hereinbefore enumerated, and possibly others, is made to conform to the curvature 10 of the surface 6 of said head, while the marginal portion 13 of said plate originally extending radially beyond said head is bent, folded, or crimped reversely therebeneath so as to completely surround the peripheral portion 15 of the head and thereafter rest beneath and protected by said head from the usual road traffic which frequently passes over and in direct contact with the marker.

It is to be understood in considering this invention that I provide a substantially permanent light-reflecting marker for directing traffic, indicating boundaries, limits, words or instructions or information, etc. upon the surface of highways and that said light-reflecting character may be provided and its permanency insured in any suitable manner, such for instance as by forming the entire marker of Monel, ascoloy, or similar light-refracting, non-corrosive alloy, or other material, by covering the surface of a relatively harder head portion of the marker when made of iron, steel or the like with a plate of suitable material or by surfacing the exposed portion of said head by electro-plating, enamelling, or otherwise coating the same as hereinbefore referred to.

Having thus described my invention, what I claim and desire to protect by Letters Patent of the United States is:—

45 1. A marker for guiding traffic, comprising a head portion, a plate covering the otherwise exposed surface of said head, the marginal portion of said plate being reversely turned about the periphery of said head, to 50 unitarily secure said plate to said head, and means carried by said head to secure said marker to a given surface.

55 2. A marker for guiding traffic, comprising a head portion, a plate covering a portion of said head upon one side thereof and having its radially outer portion reversely turned about the periphery of said head to unitarily secure said plate to said head, and means carried by said head to secure said marker 60 to a given surface.

65 3. A marker for guiding traffic, comprising a head portion, a plate covering a portion of said head upon one side thereof and having its radially outer portion reversely turned about the periphery of said head to unitarily

secure said plate to said head, and a split projection carried by said head portion and adapted to enter and expand within the material of a given surface upon said marker being driven by a suitable tool in engagement 70 with said head portion.

4. A surface marker for vehicle traffic, comprising a head, an integral fastening means associated therewith and adapted to extend into the material where the marker is positioned, and a sheath of light-reflecting material fastened to said head and having the exposed surface of said sheath of convex formation, said fastening means comprising a substantially cylindrical member having independent prongs at one end thereof normally extending within the cylindrical limits of the remaining portion of said member, the inner surface of each prong having at least one tapered surface which engages the material into which the marker is forced to cause said prong to be flexed outwardly from its normal original position.

In testimony whereof I have affixed my signature.

ROBERT FOSTER.
